UNITED STATES PATENT OFFICE.

HERBERT ABRAHAM, OF NEW YORK, N. Y., ASSIGNOR TO THE RUBEROID COMPANY,
A CORPORATION OF NEW JERSEY.

UNIT SHINGLE.

Application filed March 23, 1922. Serial No. 545,954.

To all whom it may concern:

Be it known that I, HERBERT ABRAHAM, a citizen of the United States, residing at the city, county, and State of New York, have 5 invented certain new and useful Improvements in Unit Shingles, of which the following is a specification.

This invention relates to an improved reversible unit shingle made of prepared 10 roofing consisting of felt or fibrous material saturated and coated with bituminous compositions, and generally faced on one side with granules of mineral matter.

The invention broadly stated consists in 15 the provisions of a reversible oblong unit shingle having one of its end portions of reduced width and having a pair of hooks indented in opposite parts of each of the lateral marginal edges of its other end portion.

The units are so constructed that when laid with the wider ends downward, each will interlock with the laterally adjacent units of both the next upper and lower 25 courses in the manner described in my application Serial No. 476,476, filed May 6, 1921, and when laid with the narrow ends downward, they will be self-spacing with 30 relation to the laterally adjacent units of the same row or course as well as with successive courses.

An important feature of the invention is the fact that the innermost pair of hooks function also as gauges for aligning the 35 units, in proper relation to the roof edges, when the end portions of reduced width are laid downward.

In the accompanying drawings illustrating the invention,

40 Figure 1 is a plan view of my improved reversible unit shingle.

Figure 2 is a plan view of several of the units laid in interlocking relation, and,

45 Figure 3 is a similar view of the units laid in self-spacing relation.

Referring now to Figure 1, of the drawings, 1 indicates a unit shingle of general oblong shape having a pair of hooks 2-3 indented in opposite parts of the lateral 50 marginal edges of the lower end portion, as fully described in my patent application Serial No. 476,476, filed May 6, 1921, and having its upper end portion of reduced width to form similar shoulders 4 in each 55 of its sides. The shoulders are spaced

downwardly from the upper edge as seen in Fig. 1, the distance that the unit is intended to be exposed when laid in reversed position, that is with the upper end down, as shown in Figure 3.

When the units are laid in interlocking relation, as shown in Figure 2, the hooks 2 and 3 at either side will engage with corresponding hooks of the laterally adjacent units of the next upper and lower rows, thereby forming a roof covering having rectangular shaped exposed portions arranged in horizontally staggered order, and in which the several units are interlocked.

As hereinbefore pointed out, the units 70 may also be laid in the reverse position of that shown in Fig. 1. When the units are thus laid side by side in a row to form a course, the shoulders will automatically space the butt ends of the contiguous shingles, and at the same time define the proper overlap of successive courses. The units of the succeeding course are then laid so that their butt ends come into horizontal alignment with the shoulders of the units of the 75 lower course, and with the middles of the upper units substantially in vertical alignment with the upper ends of the slots that separate the butts of the units of the lower course. In this manner a roof is formed 80 in which the butts of the shingles of each course are separated exactly the proper distance and in which the exposed portions of the shingles are also automatically provided as seen in Figure 3.

The parts of the unit are preferably so constructed that the points of the hooks 2 will constitute gauges for aligning the units, so that their edges when laid will always be in parallel relation with the corresponding 95 edges of the roof. When the units of substantially the proportions shown are laid as indicated in Figure 3, that is, so that the points of the two hooks 2 of each unit will fall in line with the top edge of the units of an immediately underlying course, at the same time the butts of the units of the overlying course fall into alignment with the shoulders of those of the underlying course, then these three guide points will insure parallelism of the shingle edges all over the 100 roof without the extra labor of providing chalk lines as guides.

From the foregoing description it will be understood that this improvement provides 110

reversible unit shingles that may be laid in either of two ways to produce an attractive and efficient roof covering. This is advantageous and economical for the dealer in that it permits him to offer his customers alternative types of roofs from but a single supply of shingle units.

What I claim is:

1. Prepared roofing shingles adapted to
10 be laid in alternative positions in overlapping courses to form a roof, each unit comprising a substantially oblong shaped body having a pair of hooks indented in opposite parts of each of the sides of one of its end
15 portions, which hooks when the units are laid in one position, are adapted to interlock with corresponding hooks of the laterally adjacent units of the next lower and upper courses respectively, and having its
20 other end portion reduced in width to form a shoulder in opposite parts of each of the sides at substantially the distance from the narrower end that the unit is intended to be exposed when laid in reversed position.

2. Prepared roofing shingles adapted to 25
be laid in alternative positions in overlapping courses to form a roof, each unit comprising a substantially oblong shaped body having a pair of hooks indented in opposite parts of each of the sides of one of its end 30 portions, which hooks when the units are laid in one position, are adapted to interlock with corresponding hooks of the laterally adjacent units of the next lower and upper courses respectively, and having its 35 other end portion reduced in width to form a shoulder in opposite parts of each of the sides at substantially the distance from the narrower end that the unit is intended to be exposed when laid in reversed position, the 40 points of the hooks furtherest remote from the wider end being so disposed with relation to the narrower end as to serve as gauges in laying the units in said reversed position in parallel relation with adjacent 45 units.

HERBERT ABRAHAM.
